DESIGN FOR A PITCHER

William E. Mackelfresh, Jr., Chicago, Ill., assignor to Owens-Illinois Glass Company, Toledo, Ohio, a corporation of Ohio

Application October 1, 1936, Serial No. 65,119

Term of patent 14 years

To all whom it may concern:

Be it known that I, William E. Mackelfresh, Jr., a citizen of the United States and residing at Chicago, in the county of Cook and State of Illinois, have invented a new, original, and ornamental Design for a Pitcher, of which the following is a specification, reference being had to the accompanying drawing, forming a part thereof.

In the drawing:

Fig. 1 is a side elevational view of a pitcher showing my new design; and

Fig. 2 is a top plan view thereof.

I claim:

The ornamental design for a pitcher, substantially as shown.

WILLIAM E. MACKELFRESH, JR.
